UNITED STATES PATENT OFFICE.

WALTER H. SAVERY, OF CHICAGO, ILLINOIS.

CONTAINER.

Application filed May 20, 1921, Serial No. 471,207. Renewed January 10, 1923.

To all whom it may concern:

Be it known that I, WALTER H. SAVERY, a citizen of the United States, residing at Chicago, in the county of Cook and State 5 of Illinois, have invented new and useful Improvements in Containers, of which the following is a specification.

This invention relates to containers and an object of the invention is to provide a 10 container designed principally for use by motorists and one which will contain a quantity of detergent liquid or material and towels.

It is a well known fact that a motorist 15 frequently has to work upon the machine when away from home or garage and consequently soils his hands and great inconvenience is experienced owing to the failure to have sufficient means convenient for 20 cleaning or washing his hands and it is an object of this invention to provide a device which can be conveniently carried about by motorists and which is designed to provide an inner fluid tight compartment adapted 25 to contain a suitable liquid detergent which may be used without water for removing dirt, grease, oil or all foreign matter from the hands of the user and also to provide containing compartment for towels which 30 circles the liquid container and from which towels may be drawn as needed.

A further object of this invention is to 35 provide a device as specified which is simple in construction and may be manufactured at a relatively low cost as well as one which embodies, in connection with a removable cover, a brace adapted to increase the rigidity of the towel container.

Other objects of the invention will appear 40 in the following detailed description and in the accompanying drawing wherein:

Fig. 1 is a perspective view of the improved container,

Fig. 2 is a longitudinal section through 45 the container taken on the line 2—2 of Fig. 1.

Fig. 3 is a cross section through the container taken on the line 3—3 of Fig. 2.

Fig. 4 is an enlarged detail section taken 50 on the line 4—4 of Fig. 3.

Referring more particularly to the drawing the improved container comprises an end 1 which is provided with spaced annular flanges 2 and 3 adjacent its perimeter between which one end of the substantially cylindrical casing 4 engages. The substan-

tially cylindrical casing 4 is formed of sheet metal, and is preferably rolled from a single sheet, the edges of which are spaced as shown at 5 to provide a slit or opening 60 which extends longitudinally of the container and through which towels as indicated at A are adapted to be passed to permit engaging the towels for withdrawing them from the container. It is to be understood that the container 4 is adapted particularly for containing paper towels of any approved type which may be destroyed after use. A guide strip 6 extends the length 65 of the body 4 in close proximity to the slit 70 5 and the towels A are passed beneath this strip which also serves as an abutment against which the towel impinges when it is desired to tear off any desired length of 75 towelling.

A removable cover 8 is mounted upon the end of the container 4 remote from the end 1 and it is held against accidental removal from the container by means of interlocking outstruck portions or knobs 9. A brace 10 80 is secured to the cover 8 in any suitable manner such as by means of the outturned flanges 11 and solder, and the brace is of substantially the same thickness as the width of the slit 5. An ear 12 is formed 85 upon the brace which projects through the slit and lends rigidity to the towel receiving end of the casing 4, preventing accidental constricting of the diameter of the casing which would result in insecure connection 90 between the casing 4 and cover 8.

An annular flange 14 is formed on the inner surface of the end 1 inwardly of the flanges 2 and 3 and it has one end of the liquid container 15 attached thereto in fluid 95 tight connection. The fluid container 15 is cylindrical in shape and forms a core upon which the towelling A is wound. The cover 8 is provided with a central opening 16 through which the liquid container 15 extends and the liquid container, fitting snugly in the opening 16, is braced by the cover to prevent vibratory movement thereof within the casing 4. The end 17 of the container 15, which end projects through the opening 16, is constricted as shown at 18 and provided with an opening 19 to permit the filling of the container 15 with any approved type of detergent preferably a type 100 which can be used without the use of water. A closure cap 20 is threadably mounted upon the constricted portion 18 of the con-

tainer 15 and it is provided with a relatively small dispensing opening 21 through which the detergent liquid may be disposed. A second closure cap 22 is threadable upon the closure cap 20 and it forms a closure for the opening 21. The threads of the caps 20 and 22 are preferably opposite, that is the internal threads of the cap 20 are left handed while the internal threads of the cap 22 are right handed, therefore, when the cap 22 is unscrewed from the cap 21 the latter will be tightened upon the constricted end 18 of the container 15, which will prevent the unitary removal of the two caps 15 and will allow the proper functioning of the liquid dispensing cap 20.

It is, of course, to be understood that the invention may be constructed in various other manners and the parts associated in different relations and, therefore, I do not desire to be limited in any manner except as set forth in the claims hereunto appended.

Having thus described my invention what I claim is:

25 1. In a container, an outer casing provided with a longitudinal slit, a removable cover therefor, a brace attached to said cover, an ear formed upon said brace and extending into said slit, said ear being substantially the same width as the slit.

30 2. In a container, an outer casing pro-

vided with a longitudinal slit, a removable cover therefor, a brace attached to said cover, an ear formed upon said brace and extending into said slit, said ear being substantially the same width as the slit, a fluid container disposed axially within said casing and extending longitudinally therethrough said removable cover provided with an opening through which said fluid container extends.

35 3. In a container, an outer casing provided with a longitudinal slit, a removable cover therefor, a brace attached to said cover, an ear formed upon said brace and extending into said slit, said ear being substantially the same width as the slit, a fluid container disposed axially within said casing and extending longitudinally therethrough said removable cover provided with an opening through which said fluid container extends, a dispensing closure cap mounted on the outer end of said fluid container, and a second closure cap removably mounted over said dispensing closure cap.

40 4. In a container, an outer casing having a longitudinal slit, a removable cover for one end of said container, a brace attached to the cover, and an ear formed upon the brace and extending into the slit.

45 In testimony whereof I affix my signature.
50 WALTER H. SAVERY.
